TOBACCO SMOKING PIPE

Antheny S. Toro, Newark, N. J.

Application July 11, 1938, Serial No. 218,690

3 Claims. (Cl. 131—214)

My invention relates to tobacco smoking pipes.

An important object of the invention is to provide a pipe which will produce a cool smoke.

A further object of the invention is to provide a pipe having means for withdrawing the smoke at a point spaced from the bottom of the bowl of the pipe, whereby certain impurities will remain in the bottom portion of the bowl.

A further object of the invention is to provide means for distributing the suction action of the pipe around the periphery of the bowl.

A further object of the invention is to provide means whereby any number of upper bowl-sections may be used in connection with the lower bowl-section, thus enabling the user to have a number of pipes differing in appearance.

A further object of the invention is to provide means whereby different stems may be used in connection with the bowl.

Other objects and advantages of the invention will be apparent during the course of the following description.

In the accompanying drawing forming a part of this application and in which like numerals are employed to designate like parts throughout the same:

Figure 1 is a perspective view of the tobacco smoking pipe embodying my invention.

Figure 2 is a central vertical longitudinal section through the same.

Figure 3 is a horizontal section taken on line 3—3 of Figure 2.

Figure 4 is an exploded perspective view of the pipe, parts broken away, and,

Figure 5 to 8 inclusive are side elevations of upper bowl sections of different shapes.

In the drawing, wherein for the purpose of illustration are shown preferred embodiments of my invention, the numeral 10 designates the bowl of the pipe, as a whole, comprising an upper bowl-section 11 and a lower bowl-section 12. The upper bowl-section 11 is considerably longer than the lower bowl-section 12. Preferably formed integral with the lower bowl-section 12 is a stem section 13, as shown.

The bore of the upper bowl-section 11 is preferably counterbored, as shown at 14, for receiving a cylindrical sleeve 15, which may be formed of metal or the like, and held within the counterbore by a friction fit or by any other suitable means. The sleeve 15 is open at its opposite ends and the lower portion of the sleeve is screw-threaded, as shown at 16, to engage with screw-threads 17, formed in the side of the bore 18 of the lower bowl-section 12. It is thus seen that

the sleeve 15 serves as means to detachably connect the upper bowl-section 11 with the lower bowl-section 12, these bowl sections contacting at 19, to form an air-tight fit. The sleeve 15 is provided with a horizontal annular set of apertures 20, preferably punched outwardly, and this annular set of apertures is arranged at a point generally equi-distantly spaced from the opposite ends of the sleeve 15. At its lower end, the upper bowl-section 11 is provided at its lower end with an internal annular cut-away portion forming an internal frusto-conical wall 21. The lower bowl-section 12 is provided at its upper end with an internal annular cut-away portion providing an internal frusto-conical wall 22. The frusto-conical walls 21 and 22 register, providing an internal annular chamber, which increases in width inwardly toward the sleeve 15. This sleeve 15 extends across the inner open end of the annular chamber 23 and the annular set of outwardly stamped apertures 20 lead into the annular chamber 23, the free ends of the apertures being spaced from the frusto-conical walls 21 and 22, as shown. The sleeve 15 extending across the inner open side of the annular chamber 23 prevents the tobacco from entering this annular chamber, while the apertures 20 permit of the passage of the smoke. The sleeve 15 also serves to detachably connect the upper and lower bowl-sections 11 and 12. When the bowl-sections 11 and 12 are separated, the sleeve 15 may be removed from the upper bowl-section and the frusto-conical walls 21 and 22 may be readily cleaned or wiped off.

The stem section 13 is provided with a port 35 or passage 24, which is forked at its forward end, providing passages 25, leading into the annular groove 22. The stem section 13 has a screw-threaded recess 26, formed in its end to receive a screw-threaded extension 27, carried by a stem section 28, having a bore 29, in communication with the bore 25. The stem section 28 has the usual bite 30. It is obvious that the stem section 28 is detachably secured to the stem section 13 and that stem sections of different shapes and lengths may be secured to the stem section 13, when desired.

In Figure 4, I have shown an upper bowl-section 11a, which is circular in cross-section and tapers downwardly. This bowl-section has the sleeve 15 and associated elements and is otherwise identical with the bowl-section 11. In Figure 6, I have shown a bowl-section 11b which tapers upwardly and downwardly and is circular in cross-section. The bowl-section 11b has the

same sleeve 15 and associated elements and is otherwise identical with the bowl-section 11. In Figure 7, I have shown a bowl-section 11c having a wider intermediate portion 31 and oppositely tapering end portions 32 and provided with the sleeve 15. This bowl-section is otherwise identical with the bowl-section 11. In Figure 8, I have shown a bowl-section 11d, having an intermediate cylindrical portion 33 and oppositely tapering portions 34 and the sleeve 15. This bowl-section 11d is otherwise identical with the bowl-section 11. The bowl-section 11 may be removed from the bowl-section 12 and any one of the upper bowl-sections shown in Figures 5, 6, 7 and 8, 15 substituted therefor.

It is to be understood that the forms of my invention herewith shown and described are to be taken as preferred examples of the same and that various changes in the shape, size and arrangement of parts may be resorted to without departing from the spirit of my invention or the scope of the subjoined claims.

Having thus described my invention, I claim:

1. A tobacco smoking pipe comprising a bowl, 25 said bowl comprising separate upper and lower bowl-sections having engaging ends, said bowl-sections being provided at their engaging ends with circumferentially extending internal cut-away portions, said cut-away portions when assembled forming a circumferentially extending internal recess having its inner side open, a tubular element arranged within the bowl-sections and extending across the open side of the circumferentially extending recess and having apertures 35 in communication with the recess, said tubular element serving to cover the open side of the recess to prevent the tobacco from entering the recess and to also detachably connect the bowl-sections, and a stem having a passage 40 in communication with the circumferentially extending recess.

2. A tobacco smoking pipe comprising a bowl including separable upper and lower bowl-sections, the lower bowl-section being provided at

its upper end with an internal frusto-conical wall which flares upwardly, the lower bowl-section having a port in communication with the internal frusto-conical wall, the upper bowl-section being provided at its lower end with an 5 internal frusto-conical wall which flares downwardly, the assembled frusto-conical walls forming an annular recess which increases in width inwardly toward its inner open side, a tubular element removably mounted within the upper 10 bowl-section and projecting into the lower bowl-section and being removably mounted therein, the tubular element extending across the inner open side of the annular chamber and also serving to detachably connect the bowl-sections, the 15 tubular element having opening means leading into the annular chamber, and a stem secured to the lower bowl-section and having a bore in communication with said port.

3. A tobacco smoking pipe comprising a bowl 20 including separable upper and lower bowl-sections, the lower bowl-section having internal threads and provided at its top with an internal frusto-conical wall and also having a stem, said stem having a longitudinal passage which is 25 forked to provide passages extending upwardly and leading through the frusto-conical wall, the upper bowl-section being provided at its lower end with an internal frusto-conical wall to register with the internal frusto-conical wall of 30 the lower section, said frusto-conical walls when assembled forming an annular chamber having its inner side open, a sleeve removably held within the lower portion of the upper bowl-section and projecting below the same and having 35 its lower portion screw-threaded to enter the lower bowl-section and engaged with the threads thereof for detachably connecting the upper and lower bowl-sections, said sleeve extending across the open inner side of the annular chamber and 40 being provided between its ends with an annular set of circumferentially extending apertures leading into the annular chamber.

ANTHONY S. TORO.
